UNITED STATES PATENT OFFICE.

CHARLES P. WETMORE, OF MILWAUKEE, WISCONSIN, ASSIGNOR TO WETMORE REAMER COMPANY, OF MILWAUKEE, WISCONSIN, A CORPORATION OF WISCONSIN.

REAMER.

Application filed June 21, 1921. Serial No. 479,356.

This invention relates more particularly to expandible reamers having adjustable and renewable blades.

The main objects of the invention are to provide for free lateral adjustment of the head relative to the arbor and thus compensate for eccentricity of the work to the spindle of the machine in which the reamer is used; to locate the floating connection between the head and arbor within the head close to the blades, thereby avoiding any tendency to cramp or bind; to effectively protect the floating connection against dust, chips and grit; and generally to simplify and improve the construction and operation of reamers of this class.

The invention consists in the construction, arrangement and combination of parts as hereinafter particularly described and pointed out in the claims.

In the accompanying drawing like characters designate the same parts in the several figures.

Figure 1 is a longitudinal section on the line 1—1, Figs. 3 and 5, of an expandible floating reamer embodying the invention; Fig. 2 is a similar section of the reamer on the line 2—2, Figs. 3 and 5; Fig. 3 is a cross section of the reamer on the line 3—3, Fig. 1; Fig. 4 is a side elevation of the reamer; Fig. 5 is a front elevation of the adjustable nut for securing the reamer head or body to the arbor; and Fig. 6 is an enlarged cross section of a blade and portion of the reamer head showing one of the screws for securing the blades in the head.

The expandible floating reamer as shown by the drawing, comprises a head or body 1, and a separate arbor 2, with which the head or body has a floating connection so as to permit a free but limited lateral movement of the head with its blades transversely to its axis, and thus compensate for slight eccentricity or inaccuracy in the setting of the work relative to the driving spindle with which the reamer is connected and cause the reamer head to maintain axial alignment with the bore or hole to be reamed.

The head 1, which may be made of cylindrical or polygonal shape, is provided at its back end with an externally screwthreaded neck 3, which may be conveniently made separate therefrom and attached thereto by a screwthread, with the front end abutting against a shoulder formed on the head. The

neck, which is of hollow cylindrical shape, forms a cylindrical recess or cavity in the rear end of the head, which communicates through an axial bore in the head with a cylindrical recess formed in its front end. 60

The head or body 1 is formed with radial longitudinal blade grooves 5, having bottoms inclined outwardly from its axis towards the front end of the reamer, as shown in Figs. 1 and 2. Blades 6, removably and loosely fitted in the grooves 5, are formed in their back faces adjacent their inner edges, with longitudinal V-shaped grooves 7, as shown in Fig. 6, and are rigidly secured in place in the head by screws 8, threaded in holes formed in the head obliquely to and intersecting the back walls of the grooves 5. The grooves 7 in the backs of the blades are made to register with the screw holes in the head, so that the inner 75 ends of the locking screws 8 will engage the inwardly and rearwardly sloping sides of the grooves, as shown in Fig. 6, and thus tend to tip the outer cutting edges of the blades backward and hold their backs firmly 80 against the outer edges of the back walls of the grooves 5, and their inner front corners or edges against the bottoms and front walls of the grooves, which are of slightly greater width than the thickness of the blades, the 85 bottoms of the grooves or the inner edges of the blades being slightly inclined transversely thereto, so that the inner rear corners of the blades clear the bottoms of the grooves. This method of fastening the 90 blades in the reamer head effects their rigid support at the backs adjacent their outer edges, and at their inner front edges, thereby counteracting the tendency of the cutting strains to which the blades are subjected to tip the blades backward and cause chattering or imperfect work, and insuring even, true and smooth cutting, the construction and arrangement described above whereby this action is possible being claimed in 100 divisional application Serial No. 723,695, filed July 2, 1924.

For floating or finishing reamers of this kind, the blades are preferably set at a left hand angle, as shown in Fig. 4, and hence the 105 grooves 5 of the head in which they are held, are inclined backwardly toward the front end of the reamer. The inner edges of the blades 6 are inclined to correspond with the inclination of the bottoms of the grooves 5, 110

while their outer cutting edges are parallel with the axis of the reamer.

An adjusting nut 10, threaded on the neck 3, is beveled on its front side to engage with 5 and overhang the back ends of the blades, which are correspondingly beveled. By the adjustment of this nut, which may be graduated, as shown in Fig. 4, for this purpose, the blades are adjusted to compensate for 10 grinding or sharpening and for accurately reaming bores or holes, to exact predetermined size. The nut 10 is rigidly secured in adjusted position by a lock nut 11 threaded on the neck 3. The arbor 2 is loosely fitted 15 so as to be capable of a limited lateral movement in the recess formed by the neck 3 at the back end of the reamer head, and is formed with a central stem 13, passing loosely through the axial bore in the head 20 into the recess in its front end. A collar 14 is fitted on the stem 13, and a nut 15 is threaded on the stem next to the collar within the recess in the front end of the head or body 1, for holding the parts of the reamer 25 together. The nut 15, as shown in Figs. 1, 2 and 5, is formed in opposite sides with transverse clefts, and is provided with bearing screws 17 and locking screws 18.

As shown in Fig. 2, the bearing screws 17 30 pass through and are threaded in both leaves of the nut on opposite sides thereof, and engage at their inner or rear ends with the collar 14.

As shown in Fig. 1, the locking screws 18 35 are threaded in the front or outer leaves and engage at their inner ends the rear or inner leaves of the nut. The screws 17 are adjusted to take up wear or play between the assembled parts of the reamer, and at the 40 same time to permit the head 1 to freely shift transversely to the arbor 2, and the screws 18 are then turned inwardly against the inner leaves of the nut 15, thereby spreading the inner and outer leaves and causing the 45 screwthreads therein to bind on and lock the screws 17. The nut is provided, as shown in Fig. 5, with holes 19, for a spanner wrench.

A flat floating and driving ring or disk 21, 50 is loosely fitted in the neck 3, or the recess in the back end of the head and around the stem 13 between the head and arbor. It is formed with two pairs of diametrically opposite circular openings 23. A pair of pins 24 fixed in the arbor 2, project therefrom 55 parallel with its axis into one pair of openings 23, as shown in Figs. 1 and 3, and a pair of like or similar pins 25, fixed in the head 1, project therefrom in the opposite direction, parallel with its axis, into the other 60 pair of openings 23 in the ring 21, as shown in Figs. 2 and 3. Each of the several pins which are of smaller diameter than the openings 23, is formed in one side with a concave longitudinal groove, and between the 65 grooved side of each pin and the opposing

side of the circular opening 23 into which it projects, a cylindrical roller 27, of shorter radius than the radius of the groove in the pin, is inserted.

The screws 17 being adjusted to produce 70 an even free working fit between the collar 14 and the inner end of the front recess in the head 1 and between the opposing faces of the ring 21 and of the head and arbor, and the power required to turn the head in 75 reaming being transmitted from the arbor through the rollers 27, very little resistance is opposed to the transverse shifting movement of the head.

The floating and driving connections 80 between the arbor and head are protected against dust, grit and chips, by a removable cap 29, threaded in and closing the opening into the front recess in the head, and by a washer 30, of felt or other suitable material, 85 held in contact with the back end of the neck 3 by a groove in the front face of a flange or shoulder 31 formed on the arbor 2, thereby closing the opening into the recess in the back end of the head. 90

The floating and driving connections may be further protected as shown in Fig. 1 by guards 32 of felt, metal or other suitable material, inserted in the back ends of the blade grooves 5 next to the floating ring and 95 closing the openings therefrom into the recess in the back end of the head.

Various modifications in the details of construction and arrangement of parts of the reamer may be made without departure 100 from the principle and scope of the invention as defined in the following claims. For example, certain features of the device, such as the means shown and described for adjusting and fastening the blades in the head, 105 may be employed to advantage in roughing and semi-finishing reamers which do not have a floating connection between the head and arbor, and in other similar tools, such as milling tools. 110

I claim:

1. In a reamer, in combination, a head provided with recesses at the ends thereof and an axial bore connecting said recesses, an arbor loosely fitted into one of said recesses for lateral movement with respect to said head, said arbor being provided with a stem extending through said bore into the other of said recesses, said stem having a loose fit in said bore, a driving connection 115 arranged between said head and said arbor to permit lateral movement between said parts, and means applied to the end of said stem to hold said head and arbor in assembled relation. 120

2. In a reamer, in combination, a head provided with recesses at the ends thereof and an axial bore connecting said recesses, an arbor loosely fitted into one of said recesses for lateral movement with respect to 130

- said head, said arbor being provided with a stem extending through said bore into the other of said recesses, said stem having a loose fit in said bore, a ring arranged upon 5 said stem between said head and said arbor, said ring being provided with a plurality of openings, means arranged within each of said openings to permit lateral movement between said head and said arbor, said 10 means connecting said head and arbor for rotation together, and means applied to the end of said stem to hold said head and arbor in assembled relation.
3. In a reamer the combination of a head 15 provided with recesses in the ends connected by a central longitudinal bore, an arbor loosely fitting in the back recess of the head and having a reduced stem loosely fitting in said bore, a nut threaded on the stem within 20 the front recess for holding the head and arbor together, a floating ring loosely fitting within the back recess of the head and around the arbor stem between the arbor and head and formed with two pairs of diametrically opposite openings, longitudinally 25 grooved pins fixed in the arbor and projecting therefrom into one pair of openings in the ring, similar pins fixed in the head and projecting therefrom into the other pair of 30 openings in the ring, and rollers loosely fitted in the grooves of the pins and projecting therefrom towards the opposing sides of the openings in the ring.
4. In a reamer the combination of a head 35 provided with blades and formed with end recesses connected by an axial bore, an arbor loosely fitted in the back recess of the head and provided with an axial stem loosely fitting said bore, a floating ring loosely fitting 40 within the back recess of the head and around the arbor stem between the head and arbor and formed with two pairs of diametrically opposite openings, grooved pins 45 fixed in the arbor and projecting longitudinally therefrom into one pair of openings in the ring, similar pins fixed in the head and projecting therefrom into the other pair of openings in the ring, rollers loosely fitted in the grooves in the pins and projecting 50 therefrom into engagement with the opposite sides of the openings in the ring, a collar fitted on the arbor stem within the front recess of the head, a nut threaded on the stem next to the collar and transversely 55 cleft on opposite sides, adjustable bearing screws threaded in and passing through the cleft sides of the nut into engagement with the collar, and locking screws threaded in the outer leaves and engaging the inner 60 leaves of the nut.
5. In a reamer the combination of a head provided with recesses in the ends connected by an axial bore, an arbor loosely fitted in the back recess and having a central stem 65 passing loosely through said bore, a floating 70 ring loosely fitting within the back recess of the head, and around the stem of the arbor and formed with two pairs of diametrically opposite circular openings, pins fixed in the arbor and projecting therefrom into one pair 75 of openings in the ring, similar pins fixed in the head and projecting therefrom into the other pair of openings in the ring, the several pins being of smaller diameter than the openings in the ring and formed with 80 concave longitudinal grooves, rollers of shorter radius than the radius of the grooves in the pins interposed between the grooved sides of the pins and the opposing sides of the openings in the ring, and a nut threaded 85 on the arbor stem within the front recess of the head, for holding the head and arbor with the interposed floating ring, together.
6. In a reamer the combination of a head 90 provided with recesses in the ends connected by a reduced axial bore, an arbor loosely fitted in the back recess of the head and formed with a stem loosely fitted in the reduced bore of the head and with a laterally grooved flange next to the inner end of 95 the head, a floating ring loosely fitted within the back recess of the head and around the stem of the arbor and formed with two pairs of diametrically opposite openings, concave-grooved pins fixed in the arbor and 100 projecting therefrom loosely into a pair of openings in the ring, similar pins fixed in the head and projecting therefrom loosely into the other pair of openings in the ring, rollers loosely fitted in the grooves of the pins and 105 projecting therefrom into engagement with the opposing sides of the openings in the ring, a nut threaded on the arbor stem within the front recess in the head and adjustably holding the arbor and head with the 110 interposed ring together, a removable dust cap for closing the opening into the front recess of the head, and a dust washer held in the grooved flange on the arbor in contact with the adjacent end of the head.
7. In a reamer the combination of a head 115 formed with an axial bore, an arbor having at its front end a reduced axial stem passing through and having lateral play in said bore, a flat floating and driving ring loosely encircling the stem between the head and arbor and formed with two pairs of diametrically opposite openings, pins projecting longitudinally from the arbor loosely 120 into one pair of openings, pins projecting in the opposite direction loosely into the other pair of openings in the ring, and a member adjustably mounted on the stem for holding the head and arbor together and taking up play between the opposing faces 125 of the floating ring, and of the arbor and head.
8. In a reamer, a hollow head provided with a partition intermediate the ends thereof to form recesses on either side of said par- 130

tition, said partition being provided with a central opening connecting said recesses, an arbor having one end thereof fitted into one of said recesses and provided with a stem 5 extending through said opening into the other of said recesses, and means applied to the end of said stem for holding said head and arbor in assembled relation.

9. In a reamer, a head provided with an 10 axial opening, an arbor having one end thereof reduced to form a stem, said stem extending loosely through said opening, means applied to the end of said stem for holding said head and arbor against axial 15 movement with respect to each other but permitting relative transverse movement of the same, a ring loosely mounted on said stem between said head and said arbor, and means associated with said ring and coacting 20 with said head and arbor whereby the latter are connected for rotation together and for transverse movement with respect to each other.

10. In a reamer, a hollow head provided 25 with a partition intermediate the ends thereof to form recesses on either side of said partition, said partition being provided with a central opening connecting said recesses, an arbor having one end thereof 30 loosely fitted into one of said recesses and reduced to provide a stem extending loosely through said opening into the other of said recesses whereby said head is permitted to move transversely with respect to said arbor, means applied to the end of said stem 35 and arranged in said last-mentioned recess and engaging said partition whereby said head is held against axial movement with respect to said arbor but permitted to move 40 transversely with respect to the latter, a ring loosely mounted on said stem and arranged between said head and said arbor, and means associated with said ring and coacting 45 with said head and arbor whereby the latter are connected for rotation together

and for transverse movement with respect to each other.

11. In a reamer, a head provided with a recess in one end thereof, an arbor provided with a flange and a portion extending 50 beyond the latter and fitting loosely in said recess, means arranged in said recess and coacting with said head and arbor for connecting the latter for rotation together while permitting relative lateral play of the 55 same with respect to each other, packing material arranged between and held in position by said flange and the adjacent end of said head for preventing the entrance of foreign matter between the same into said recess, and means for holding said head and arbor in assembled relation.

12. In a reamer, a head, an arbor having a portion thereof extending through said head, a nut screwed upon the end of said portion and provided with a transverse cleft forming leaves, a screw passing through said leaves and arranged to hold said head and arbor against relative axial movement and to take up play between the latter, and a 65 second screw passing through one of said leaves and engaging the other of said leaves whereby the latter are spread apart and said screws and said nut locked in adjusted position. 70

13. In a reamer, a head provided with an axial opening, an arbor provided with a grooved flange and a stem extending beyond the latter, said stem extending through said opening, packing material arranged in 80 the groove of said flange between the latter and the adjacent end of said head, and means applied to the end of said stem for holding said head and arbor in assembled relation with said end of said head in sealing 85 engagement with said packing material.

In witness whereof I hereto affix my signature.

CHARLES P. WETMORE.
